UNITED STATES PATENT OFFICE.

MORRIS HEYMANN, OF ANNAPOLIS, MARYLAND.

EXTENSION-TABLE.

1,244,208.

Specification of Letters Patent. Patented Oct. 23, 1917.

Application filed August 31, 1916. Serial No. 117,959.

To all whom it may concern:

Be it known that I, MORRIS HEYMANN, a subject of the Czar of Russia, residing at Annapolis, in the county of Anne Arundel,

5 State of Maryland, have invented a new and useful Extension-Table; and I do hereby declare the following to be a full, clear, and exact description of the invention, such as will enable others skilled in the art to which

10 it appertains to make and use the same.

This invention relates to a new and useful extension table, and particularly one in which the extension leaf is carried by the table.

15 One of the objects of the invention is to provide an extension table consisting of two sections slidably united, and provided with a sectional extension leaf, which, when not in use, is suspended below the sections of the 20 table, and when the two sections are extended, the extension leaf may be moved up between the two sections of the table, thereby increasing the size of the table top.

A further object of the invention is the 25 provision of guide means for the sectional leaf whereby the sectional extension leaf may be guided up between the two table sections.

A further object of the invention is to provide guide means for the two table top sections.

In practical fields, the details of construction may necessitate alterations falling within the scope of what is claimed.

35 The invention comprises further features and combination of parts, as hereinafter set forth, shown in the drawings, and claimed.

In the drawings:—

Figure 1 is a view in perspective of the 40 improved extension table constructed in accordance with the invention.

Fig. 2 is a plan view of the extension table.

Fig. 3 is a cross sectional view showing 45 the sectional extension leaf out of coöperation between the two sections of the table.

Fig. 4 is a sectional view on line 4—4 of Fig. 3.

Fig. 5 is a bottom plan view of the extension leaf.

Fig. 6 is an enlarged sectional view longitudinally through the structure shown in Fig. 5.

Referring more especially to the drawings, 1 designates a suitable center post or pedestal having the supporting legs 2. Se-

cured upon the top or upper end of said pedestal or post by means of screws 3 is a cross piece 4, to which, by means of screws 5, parallel strips or bars 6 are secured, 60 which extend transversely of the cross piece 4. Secured to the strips or bars 6 by means of the angle brackets 7, and extending laterally from the outer faces of said strips or bars 6 are extensions 8 having 65 guide grooves 9, as shown in the drawings. The table top consists of the two sections 10, which may be any suitable shape or configuration, but which, in the present instance, are semi-circular in plan view, and 70 are provided with the usual downwardly extending semi-circular flanges 11. Carried by the under faces of the table top sections 10 and projecting from the inner circumference of the flanges 11, are extensions 12, 75 having guide ribs 13, which engage the guide grooves 9 of the extensions 8, whereby through the medium of the guide extensions 8 and 12, the table top sections 10, are movably supported upon and with relation to the strips or bars 6, so that the 80 table top sections may be moved toward and from each other. The adjacent edges of the table top sections 10 have guide grooves 14. The adjacent faces of the strips 85 or bars 6 have guide grooves 15 and 16. The opposing grooves 15 are correspondingly shaped, while the opposing grooves 16 are correspondingly shaped. The corresponding ends of both grooves 15 are pro-

90 vided with gradual upwardly extending inclined portions 17, which merge into the grooves 14 at one side of the table. The corresponding ends of the grooves 16 merge into substantially semi-circular 95 grooves 18 opposite the inclined portions 17, and which semi-circular portions 18 merge into the grooves 14 opposite where the inclined portions 17 merge into said grooves 14. The extension leaf for the 100 table consists of the two sections 19 and 20, and each section consists of a plurality of slats or strips 21, which are hingedly united by the hinges 22. It is to be noted that when the extension leaf is not in use, 105 the lugs 23, at the opposite ends of the slats or strips, are engaging the opposing grooves 15 and 16 of the strips or bars 6, in which case the table top sections 10 may be moved toward and engage each other. Furthermore, 110 when the extension leaf is not in use, the section 19 of said extension leaf is in-

verted, while the section 20 is not. It is to be noted that the hinges of the slats of the section 19 of the extension leaf are of the ordinary type, in which case the slats 5 of the section 19 will move pivotally relative to each other, as the lugs of said slats follow the semi-circular portions 18 of the guide grooves 16, when moving the section 19 of the extension leaf upwardly between 10 the adjacent edges of the table top sections. Owing to the upper face of the section 20 of the extension leaf, at all times, remaining uppermost, the adjacent lower portions of the slats of the section 19 must separate, 15 when the lugs of the slats of the section 20 follow the inclined portions 17 of the guide grooves 15, when moving the section 20 upwardly between the adjacent edges of the table top sections 10. In order that the 20 lower portions of said slats or strips of the section 20 of the extension leaf may separate, one end of each leaf of each hinged connection of the slats of the section 20, is provided with an elongated bearing 24 for 25 the hinge pin, thereby allowing looseness of play between the hinged connections of the slats of the section 20. When making the table longer, the table sections 10 are separated sufficiently, so that their adjacent 30 edges will be flush with the adjacent faces of the strips or bars 6. The section 20 of the extension leaf is then moved in the direction of the arrow *a*, until the lugs of the strips or slats of the section 20 engage the 35 guide grooves 14. The section 19 of the extension leaf is then moved in the direction of the arrow *b*, the lugs of the slats of the section 19 following the semi-circular portions 18 of the guide grooves 16, until 40 said lugs engage the opposing guide grooves 14, then the two sections 19 and 20 of the extension leaf are arranged in their proper 45 positions, as shown clearly in Figs. 1 and 2.

The invention having been set forth, what 45 is claimed as new and useful is:—

1. In an extension table, a supporting pedestal, a pair of extensible table top sections, means on the pedestal and with which the table top sections have sliding connec-

tions, whereby the sections may be moved 50 toward and from each other, an extension leaf consisting of two sections, said means having a compartment for the extension leaf, the adjacent edges of the table top sections having guide grooves, said compartment upon its opposite faces having two sets of guide grooves, and means on the opposite edges of the two sections of the leaf engaging said two sets of grooves, said last mentioned grooves having curved and 55 inclined portions at corresponding opposite ends merging into the grooves of the table top sections, whereby said leaf sections may be moved between said table top sections when extended, said sections of the extension leaf being constituted of a plurality of slats hingedly united, the hinges of the slats of one section having elongated slot connections, thereby affording looseness of play 60 whereby the slats may separate when moving up the inclined portions of one set of 65 said grooves.

2. In an extension table, a pedestal, a member fixed across the upper end of the pedestal, a pair of opposing bars fixed to 75 and extending transversely of said member thereby forming a trough, said bars having lateral pieces, extensible table top sections having sliding connections with said lateral pieces, the adjacent edges of the table top 80 sections having guide grooves, the inner opposing side faces of the trough having two sets of guide grooves, each set extending horizontally and in parallelism, the corresponding opposite ends of which merge into 85 the grooves of the table top sections, and a flexible extension table leaf consisting of two parts having means engaging the two sets of grooves of the trough and adapted to engage the grooves of the table top sections 90 when said sections are extended.

In testimony whereof I have signed my name to this specification in the presence of two subscribing witnesses.

MORRIS HEYMANN.
